CLAIM

We claim the ornamental design for the wall mounted automated teller machine, as shown and described.

DESCRIPTION

FIG. 1 is a front perspective view of a wall mounted automated teller machine showing our new design;

FIG. 2 is a top view;

FIG. 3 is a front elevational view;

FIG. 4 is a bottom view;

FIG. 5 is a right side view;

FIG. 6 is a left side view; and,

FIG. 7 is a rear view.

The broken line showing of the wall in FIGS. 1 through 6 is for illustrative purposes only and forms no part of the claimed design.
